UNITED STATES PATENT OFFICE

JOHN F. SCHYLANDER, OF CHICAGO, ILLINOIS, ASSIGNOR TO JAS. P. MARSH & COMPANY, OF CHICAGO, ILLINOIS, A CORPORATION OF ILLINOIS

AIR VALVE

Application filed April 9, 1927. Serial No. 182,411.

My invention relates to that general class of devices known as valves and particularly automatic air valves or the like. More especially the same relates to an improved housing or casing construction made up of stampings. The invention has among its objects the production of a device of the kind described that is simple, durable, compact, efficient, inexpensive and satisfactory for use wherever found applicable. The invention has particularly as an object the production of a base provided with a nipple, all constructed entirely of stampings which, when operatively assembled and secured together, is of great strength and light weight. It has as an object the production of a device made up of a combination of stampings which, when assembled together, results in a more satisfactory inexpensive device, than constructions heretofore employed in devices of this kind. Many objects and advantages of the construction herein shown and described will be obvious to those skilled in the art from the disclosure herein given.

25 To this end my invention consists in the novel construction, arrangement and combination of parts herein shown and described, and more particularly pointed out in the claims.

30 In the drawings, wherein like reference characters indicate like or corresponding parts:

- Fig. 1 is a sectional view through my improved valve;
- 35 Fig. 2 is a sectional view taken substantially on line 2—2 of Fig. 1;
- Fig. 3 is a sectional view taken substantially on line 3—3 of Fig. 1;
- 40 Fig. 4 is a top plan view of the base with the upper part 2 removed;
- Fig. 5 is a sectional view taken on line 5—5 of Fig. 4;
- 45 Fig. 6 is a perspective view of the base before application of the nipple;
- Fig. 7 is a perspective view of the nipple partially completed;
- 50 Fig. 8 is a sectional view taken substantially on line 8—8 of Fig. 9 and
- Fig. 9 is a bottom view of the base and nipple.

Referring to the drawings, in which an embodiment of the invention is shown, the complete housing of my improved valve consists of a cup-shaped base part 1 provided with the nipple 9 and the housing part 2, the same all being stampings. The base part 1 is stamped out cup-shaped and offset outwardly at 3 about a portion of its periphery to form the rim 4 with a shoulder 5 at the interior. The shoulder 5 extends around the base to points at either side of the nipple opening 7. At the side where the opening is, the face of the base is substantially straight from top to bottom, as will be obvious by referring to Figs. 1 and 6, the bottom portion extending more or less straight from the center as at 6 to the face 6'. The bottom and wall adjacent the opening while curved is not a true semi-spherical surface as may be seen by reference to Figs. 1, 6 and 8, the advantage of this being 55 hereinafter pointed out. It will be noted that the nipple is eccentrically disposed with respect to the curvature (see Fig. 8) of the bottom and that this construction prevents displacement of the base part 1 upon the bottom. 60 The nipple is stamped out from a disc to substantially the form shown in Fig. 7 so as to provide a nipple body portion or flange 8 with the shank 9, the shank being tubular as indicated at 10. At a later operation the shank is cut off at 14 (see Fig. 4) and externally threaded as indicated at 15 so that the opening 10 extends entirely through the same. The body portion 8 is cut off straight as indicated at 11, with a shoulder 12 and shoulder 12' formed at either side, the parts being so constructed that the shoulders 12 when the nipple part is secured in place, are substantially flush or level with the shoulder 5 about the base. The nipple is positioned 65 with the part 8 inside of the base and the shank 9 projecting through the opening 7. The same is then securely soldered, brazed or otherwise secured. In this connection, it may be mentioned that after the nipple part is inserted in the base and before soldered, the base is stacked about the nipple, that is to say, that it is pressed inwardly, (see 7' Figs. 1 and 6) around the shank 9 so that when solder is applied on the inside between the body 8 and 70 shank 9, the solder will be held in place by the base 1. The base part 1 is provided with a 75

100

the base 1 it will not flow out and around between the nipple shank 9 and the wall at the opening 7.

It may be mentioned that I generally prefer to cut off the shank 9 and thread the same after the nipple portion has been secured in the base portion 1. When the parts have been secured together, they constitute substantially a unitary structure with all the strength of an integral structure. This is particularly true after the plate 16 is applied as hereinafter described.

It will be particularly noted that owing to the confirmation of the base and nipple part, the surfaces in contact about the opening are not true spherical surfaces and consequently there is no chance for the nipple part to rotate or turn as would be the case if the surfaces were semi-spherical.

Mounted in the base is a plate 16 which is preferably formed with wings 17 and 18, this plate being of a size to fit in the base and rest upon the shoulder 5, the same being preferably slightly arched at its center. It will be noted that the wings 17 overlie the shoulders 12 and abut against the shoulders 12'. Where the valve is provided with the siphon tube 23, the plate is provided with the depending parts 19 and 21. The part 19 is preferably slightly turned back as indicated at 20, while the part 21 is provided with an opening through which the end of the tube 22 projects, the outer end being bent laterally as at 23. The inner end of the tube 22 is preferably flared so that it is of greater size than the opening in 21 and is thereby locked in place. An equivalent method of locking the tube in place may be employed. The tube has a limited movement or adjustment between the portions 19 and 21 and is freely rotatable in the nipple so that it does not interfere with the application of the valve to the radiator or other installation, and so that it will also hang as shown in Fig. 1, when installed.

The housing part 2 is of a size to closely fit the inner wall of the base about the rim 4 and to overlie the plate 16. It also overlies the top edge 11 of the nipple part when seated in the base, the depth of the shoulder 12' being substantially equal to the width of the plate wings 17. After the float 28 has been positioned within the casing, the housing part 2 is positioned on the base and securely soldered, brazed or otherwise secured. It will be noted that the nipple portion of the base is thus secured not only by the solder between the part 8 and the base, but also by reason of the plate 16 bearing on the shoulders 12 and on the shoulders 12', but by further securing of the upper housing 2 in place as this rests upon the face 11, as well as upon the plate 16. The nipple portion is, therefore, positively and rigidly secured in the base without relying entirely on the solder or its equivalent.

65 In fact, one of the main functions of the

solder is to form a seal and prevent leakage, as well as to assist in retaining the nipple in place. The result is that the nipple may be screwed into a radiator vent without any danger of the same breaking loose from the base. It is frequently necessary in applying the valve to a radiator to turn the valve with considerable pressure in order to bring the same to an upright position or to turn or to back it off if it is not possible to turn it to 70 operative position, which may cause it to be loosely held on the radiator. When the construction described, it may be turned down very tightly without breaking loose as would be very likely the case were the nipple only 75 secured by solder to the outside or inside of the shell and solder alone relied upon to secure it.

The particular casing part 2 shown is provided with inwardly extending grooves 26 80 forming guides for the float, as well as forming water or air passages 27. The bottom is constructed to conform to the base. The float shown is provided with a valve stem 29 having a valve face 33 arranged to cooperate with the seat 32 formed in the nozzle 30 which is suitably secured to the housing or casting. The nozzle is provided with the duct 31, the passage of air through the duct being controlled by the valve. It is believed unnecessary to 90 describe the operation of the valve as such structures are well-known in the art and familiar to those skilled therein.

It will be seen from the preceding that my improved casing consists of all metal stampings which may be secured together to afford a rigid, durable, light weight and inexpensive construction. While I have particularly referred to the application of my invention to a well-known type of automatic air valve, it 100 will be obvious that the construction is not limited to automatic air valves as it may be embodied in any device wherein it is desired to provide a nipple projecting from a housing adjacent the base and forming a part of the 105 construction.

Having thus described my invention, it is obvious that various immaterial modifications may be made in the same without departing from the spirit of my invention; hence I do 110 not wish to be understood as limiting myself to the exact form, construction, arrangement and combination of parts herein shown and described or uses mentioned.

What I claim as new and desire to secure 115 by Letters Patent is:

1. In a device of the character described, a housing, a cup shaped base receiving one end of the housing, a face on one side of the base having an opening therethrough, a nipple in said opening, and a curved flange having a center of curvature spaced from the center of said nipple on the inner end of the nipple of a shape conforming to the inner wall of the base around said opening. 125 130

2. In a device of the character described, a housing, a cup shaped base therefor, a lateral extension on the base formed with a face at one side having an opening, a nipple in said opening, and a curved flange on the inner end of said nipple conforming to the inner wall face of the base around said opening, said curved flange having one center of curvature spaced from the center of said nipple. 70
3. In a device of the character described, a housing, a hollow base stamped from a single piece of metal, a nipple forming communication with the interior of the base, and a curved flange eccentrically disposed with respect to and integral with the nipple and cooperating with the base and conforming to the interior curved surface thereof to retain the nipple against movement relative to the base. 75
4. In a device of the character described, a housing, a hollow base stamped with a single piece of metal, an inwardly extending shoulder in said base, a threaded nipple forming communication with the interior of the base, a flange integral with the nipple and conforming to the curved surface of the base and cooperating therewith to retain the nipple against movement relative the base, and means in the base resting upon said shoulder and having operative engagement with the flange to assist in retaining said flange and nipple against movement relative to the base. 80
5. In a device of the character described, a housing, a hollow base therefor stamped from a single piece of metal, a nipple forming communication with the interior of the base, a flange integral with the nipple and cooperating with the base to retain the nipple and flange against movement relative the base, a horizontal portion on the flange, a shoulder at each end of the horizontal portion, and means in the base having operative engagement with said shoulders to assist in retaining said flange and nipple against movement relative to the base. 85
6. In a device of the character described, a cup shaped base member stamped from a single piece of metal, a nipple extending through one wall of the base, a flange on the inner end of the nipple cooperating with the base to retain the nipple and flange against movement relative the base, a horizontal portion on the flange, a shoulder at each end of the flange, means in the base having operative engagement with the shoulders to assist in retaining the nipple and flange against movement, and a housing having one end fitted in the base and bearing against said means. 90
7. In a device of the character described, a cup shaped base member having a shoulder, a nipple extending through one wall of said base member, a flange on said nipple having a center of curvature spaced from the center of said nipple, said flange conforming to and cooperating with the base member to retain the nipple and flange against movement relative to the base, a straight portion on the flange, a plurality of shoulders on said straight portion, a plate resting on said shoulder of said base member and said shoulders on said flange and a housing fitting into said base member and engaging said plate to retain same on said shoulders. 95
8. In a device of the class described, a housing, a cup-shaped base therefor, a nipple extending through a wall of said base in one side thereof, said nipple having a curved flange disposed interiorly of said base and conforming to and cooperating with a curved wall of said base for retaining said nipple against movement relative to said base, a plate within said base cooperating with said flange for further retaining said nipple against movement, the ends of said plate being bent, and a movable tube extending through said nipple and through one of the bent ends of said plate, the movement of said tube being limited by said bent ends. 100
9. In a device of the class described, a housing, a cup-shaped base therefor, a nipple extending through a wall of said base in one side thereof, said nipple having a curved flange disposed interiorly of said base and conforming to and cooperating with a curved wall of said base for retaining said nipple against movement relative to said base, a plate within said base cooperating with said flange for further retaining said nipple against movement, the ends of said plate being bent, a movable tube extending through said nipple and through one of the bent ends of said plate, the movement of said tube being limited by said bent ends, and an edge of said housing engaging a portion of the flange of said nipple to further retain said nipple against movement. 105
10. In a device of the class described, a housing, a cup-shaped base therefor, a face on one side of the base having an opening therethrough, a nipple in said opening, and a curved eccentric flange upon the inner end of said nipple of a shape conforming to the inner side and bottom walls of the base around said opening, said flange and walls cooperating to retain said nipple in said base. 110
